UNITED STATES PATENT OFFICE

150,462

DESIGN FOR A MOTORCYCLE

Alfred Raymond Russell, Detroit, Mich., assignor to Saftcycle, Inc., La Crosse, Wis.

Application November 18, 1946, Serial No. 134,849

Term of patent 3½ years

(Cl. D90—8)

To all whom it may concern:

Be it known that I, Alfred Raymond Russell, a citizen of the United States of America, residing at Detroit, in the county of Wayne and State of Michigan, have invented a new, original, and ornamental Design for a Motorcycle, of which the following is a specification, reference being had to the accompanying drawing, forming a part thereof.

In the drawing:

The side of the motorcycle opposite from that shown in Figure 1 is similar to the side shown except that the starting crank lever is omitted therefrom.

I claim:

The ornamental design for a motorcycle, as shown and described.

ALFRED RAYMOND RUSSELL.
